CLEANERS FOR AIR FILTERS

Herbert L. Everroad, Denver, Colo., assignor to
 Everroad Supply Company, Denver, Colo.
 Filed Sept. 8, 1964, Ser. No. 394,881
 2 Claims. (Cl. 134—167)

This invention relates to a cleaner for air filters and more particularly to a device for cleaning the relatively large air filters as used on heavy industrial engines. Filters of this type comprise hollow cylinders having perforated walls containing a relatively thick annular packing of accordion-pleated, folded filter paper in which the foreign materials are entrapped from the air flowing to the engine. The filters are formed in a variety of differing diameters, differing lengths, and differing wall thickness and, due to the relatively tightly-packed filter paper are exceedingly difficult to clean. As a result, cleaning is rarely attempted since, it is usually more economical and less time consuming to simply replace the clogged filters with new filters.

The principal object of this invention is to provide an economical, highly efficient and easily used filter cleaning device by means of which the dust, sand, dirt and other debris can be quickly and efficiently removed from used filters to restore the original free-air flow condition.

Another object is to provide a filter cleaning device for the above purpose which will not require driving motors or other power devices and which eliminates all hand labor.

A further object is to so construct the filter cleaner that filters of various sizes and various wall thicknesses can be cleaned without changes or adjustments in the cleaner and without damage to the filter elements.

Other objects and advantages reside in the detail construction of the invention, which is designed for simplicity, economy and efficiency. These will become more apparent from the following description.

In the following detailed description of the invention, reference is made to the accompanying drawing which forms a part hereof. Like numerals refer to like parts in all views of the drawing and throughout the description.

In the drawing:

FIG. 1 is a side-elevational view of the improved filter cleaner as it would appear in its outer container ready for use;

FIG. 2 is a vertical diametric section through the outer container showing the internal cleaning elements;

FIG. 3 is a top view of the complete unit;

FIG. 4 is an enlarged, fragmentary, detail section to be later described;

FIG. 5 is a perspective illustration showing the type of filter the invention is more particularly designed to clean; and

FIG. 6 is a fragmentary detail view of a supply connection incorporating a T-fitting 43 and two manual shut-off valves 44 and 45 which may be used to supply two different fluids either sequentially or admixed to the filter cleaner.

The cleaning elements are assembled as a complete unit adapted to be removably suspended in an outer container 10 provided with a drain plug 41 in its bottom. The cleaning unit employs an outer frame having a circular top rod 11 from which, preferably three, vertical outer side rods 12 depend to support a horizontal open bottom member 13. The upper extremities of the outer side rods are bent outwardly and downwardly to form hooks 14 which are hung from notches 15 formed in the upper edge of the outer container 10.

An inner rod frame is supported in radially-spaced relation within the outer frame. The inner rod frame comprises three vertical suspension rods 16, each extending

2

inwardly and downwardly, as shown at 17, from the circular top rod 11 of the outer frame, thence vertically downward to support an open horizontal platform 18. The suspension rods are rigidly maintained in vertically-spaced relation by means of a brace ring 39 welded thereto and extending downwardly to the open horizontal platform 18. The platform 18 is circular and is formed with radially-extending spokes 19 which support a horizontal rod ring 20 of relatively small diameter about the axis of the platform 18.

5 A water supply pipe 21 is welded or otherwise secured to the outer frame and terminates at its upper extremity in an outwardly extending shutoff valve 22, to which a conventional hose may be attached, and at its lower extremity in a horizontal pipe 23. The horizontal pipe 23 is welded or otherwise secured to the bottom member 13 and extends to an upturned elbow 24, at the axis of the frame upon which a swivel fitting 25 is mounted. The swivel fitting is of any conventional type. As illustrated, 10 a vertical, tubular stem 27 is rotatably mounted in the fitting 25 and carries a coupling 26 which is maintained in sealed engagement with the fitting 25 by means of a compression spring 28. Thus, the coupling 26 is free to rotate on the fitting 25 at the axis of the frames.

15 The coupling 26 furnishes water to a cross fitting 29 from the sides of which two radial pipes 30 oppositely project to support, at their outer extremities, vertical outer spray pipes 31 in the annular space between the outer side rods 12 and the suspension rods 16. The spray pipes are 20 closed at their tops by means of suitable caps 33. A plurality of outside spray heads 32 are mounted on and faced inward at a slight radial tangent from each of the spray pipes 31.

25 A riser pipe 34 arises from the upper outlet of the cross fitting 29 upon which a plurality of T-fittings 35 are alternately joined by means of pipe nipples 36. The T-fittings 35 and the nipples 36 form a center spray standard 37. An inside spray head 38 is mounted in each of the T-fittings 35 to direct water sprays radially outward from the center spray standard 37. It is preferred to employ 30 a quick detachable coupler 42 to connect the riser pipe 34 to the cross fitting 29.

35 The filter cleaner of this invention is designed to clean 40 hollow, cylindrical, industrial air filters such as illustrated at 40 in FIG. 5. The filter 40 is rested upon the horizontal platform 18 so as to surround the standard 37, as indicated in broken line in FIG. 2. Water is admitted to the supply pipe 21 and discharges against the exterior of the filter 40 from the outside spray heads 32 and against the interior surface from the inside spray heads 38 on the standard 37. Since the outer spray heads are positioned at a slightly inclined radial angle, the outer sprays will react to rotate all of the sprays about the axis of the standard.

45 The inner frame has a diameter in excess of the largest 50 expected filter and the spray pipes have a length in excess of the longest expected filter so that no adjustments are necessary to handle any standard size of filter.

55 While a specific form of the improvement has been 60 described and illustrated herein, it is to be understood that the same may be varied, within the scope of the appended claims, without departing from the spirit of the invention.

65 Having thus described the invention, what is claimed and desired secured by Letters Patent is:

70 1. A device for cleaning engine air filters comprising: an outer open frame consisting of vertical side rods joining and supporting an open bottom member; an inner open frame supported concentrically within and in spaced relation to said outer frame, said inner frame consisting of vertical suspension rods extending downwardly to an open horizontal platform for supporting a tubular engine

air filter; a water supply conduit supported by said bottom member and extending concentrically upward therefrom; a rotatable swivel fitting mounted on said conduit below said platform; a cross fitting mounted on said swivel fitting; spray pipes extending oppositely outward from said cross fitting and upwardly between said outer frame and said inner frame at each side of said inner frame; a plurality of outer spray heads mounted on said spray pipes and positioned to direct water sprays radially inward against the external surface of an air filter resting on said platform; a riser standard mounted on said cross fitting and extending axially upward through said platform; and a plurality of inner spray heads mounted on said stand-

10

ard and positioned to direct water sprays radially outward against the inner surface of the air filter resting on said platform.

5 2. A device for cleaning engine air filters as described in claim 1 in which said side rods terminate at their upper extremities in outwardly extending hooks adapted to engage the rim of an outer container to suspend said frames therein.
